G. WINGENDER.
DRIP TRAY FOR DISHES.
APPLICATION FILED DEC. 16, 1911.

1,025,178.

Patented May 7, 1912.

UNITED STATES PATENT OFFICE.

GEORGE WINGENDER, OF NEW YORK, N. Y.

DRIP-TRAY FOR DISHES.

1,025,178.

Specification of Letters Patent.

Patented May 7, 1912.

Application filed December 18, 1911. Serial No. 666,141.

To all whom it may concern:

Be it known that I, GEORGE WINGENDER, a subject of the Emperor of Germany, residing at Manhattan borough, city, county, 5 and State of New York, have invented certain new and useful Improvements in Drip-Trays for Dishes, of which the following is a full, clear, and exact description.

This invention relates to an improvement 10 in drip-trays for dishes or the like, the object being to provide a simple and inexpensive device of this character which can be placed upon the usual kitchen washtubs or table adjacent a sink, dishpan or other device in which dishes are washed, and in which the washed dishes can be placed and allowed to drip or drain.

I will now proceed to describe my invention in detail, the novel features of which I 20 will finally point out in the claim, reference being had to the accompanying drawing, forming part hereof, wherein:

Figure 1 is a top plan view of my improved drip-tray; Fig. 2 is a longitudinal 25 sectional view thereof, on an enlarged scale; and Fig. 3 is a cross-sectional view on a slightly reduced scale, the section being taken on a line *a—a* in Fig. 1.

Referring to the drawing, my improved 30 drip-tray comprises a frame 1, which consists of the side members 2, rear member 3, and a platform or support 4, which is preferably corrugated. As can be seen in Figs. 2 and 3, the support 4 is carried by the frame 35 1 and is mounted intermediate the top and bottom edges of the frame members.

To support, or rather to adapt the frame 1 to carry the platform 4, I provide the 40 frame members 2 and 3 with a pocket 5, the said pocket being formed by striking up the material of the frame members, as shown in Figs. 2 and 3. After the pocket 5 is struck up from the material of the frame members, the platform 4 can be slid in from the open 45 end 6 of the frame 1, before the members 2 thereof are bent inwardly or toward each other. After the frame members 2 have been bent inwardly, as shown in Fig. 1, the platform 4 will be securely held in the 50 pocket 5 and prevented from being pulled out.

To prevent the outer ends of the frame members 2 from becoming forced apart or 55 away from each other, I provide a tie-rod 7, each end of which enters the open end of

the beading 8, which is located at the upper edge of the frame members. The lower edge of the said frame members is also provided with a beading 9. The beadings 8 and 9 not only strengthen the structure, but also prevent the scratching of the objects upon which the tray may be placed.

As can be seen in Fig. 2, the frame 1, or rather the side members of the frame 1, are tapered, and it will also be seen by reference 65 to the said figure, that the platform 4 is inclined, in order that the water from the dishes will run off. The corrugations 10 in the platform 4 permit of the running off of the water rapidly.

In order that small dishes can be allowed 70 to drip, I provide a grid, comprising the plate 11, provided with slots 12, whereby bars 13 are produced. The grid is supported in the forward end of the frame 1, as 75 shown. Small dishes can be placed in the slots 12 and allowed to drip, as shown by dotted lines 13' in Fig. 2. The space 14 between the grid and rear member 3 of the frame 1 is adapted to receive large dishes 80 or dishes which cannot be held in the slots 12. The space 14 is provided not only to receive large dishes, but also cutlery, pots, pans, &c.

To removably support the grid or plate 85 11, I provide the same, at the rear end thereof, with pins 17, which are outwardly bent, as shown, the bent ends being adapted to enter slots 18 in the side members 2 of the frame 1. In connection with the pins 17, I 90 provide pins 15, at the forward end of the grid, which are downwardly bent, as shown, the downwardly bent pins being adapted to enter sockets 16, which are formed integral with the side members of the frame.

Should I desire to remove the grid 11, I would pull the forward end thereof upwardly, thereby causing the pins 15 to leave the sockets 16. After having lifted the pins 15 out of the sockets 16, I would move the 100 plate 11 sidewise enough to cause the pins 17 to leave the slots 18. It will, of course, be understood that the plate 11 will fit loosely in the frame 1, sufficiently, however, to permit of the sidewise movement of the 105 said plate. Instead of removing the plate 11 I may swing it upwardly at its forward end and swing it rearwardly, the pins 17 acting as a pivot.

Having now described my invention, what 110

I claim and desire to secure by Letters Patent is:

A drip-tray, comprising a frame consisting of a rear member and side members bent inwardly or toward each other at the free ends thereof, a tie-rod connecting said inwardly bent ends, said side-members being provided with slots disposed longitudinally thereof, a grid carried by said frame, pins carried by said grid adapted to take into the slots in the side members of said frame, pins carried by said grid at the forward

end thereof, and pockets carried by said frame adapted to receive the pins last named, said grid being tapered to correspond with the inwardly bent ends of the side members of said frame. 15

Signed at New York city, N. Y. this 13th day of December, 1911.

GEORGE WINGENDER.
